(57) **CLAIM**

The ornamental design for a pipe sealing gasket, as shown and described.

DESCRIPTION

FIG. 1 is a front perspective view of the pipe sealing gasket showing the new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and,

FIG. 9 is an enlarged cross-section view taken from area 9-9 of FIG. 2.

The stippled shading shown in the drawings represents a contrast in appearance.

1 Claim, 6 Drawing Sheets
